ABSTRACT: This invention discloses an envelope or container used in the handling of film and prints for photo finishing, the container being provided with a number and a removable label attached to the envelope, having the same identification number as the envelope, to be placed on the negative or exposed film to provide positive identification of the film placed in the envelope, and a removable tab providing a receipt to the owner of the film which also has the same identification number as the label and the envelope, so that the identification is maintained throughout the processing and printing of the photo finishing step.

**ENVELOPE WITH REMOVABLE IDENTIFICATION
LABEL**

The principal objects of the present invention are: to provide envelopes or containers used by merchants to contain an order for processing films, making prints, or repair of small items left by customers to be processed or serviced for delivery at a later date.

Other objects of the present invention are: to provide an envelope having a front panel, foldable side panels forming a back panel, and a bottom flap for closing one end of the envelope, and said bottom flap having an extension secured to the bottom flap by a perforated line which may be torn off and which is provided with a number corresponding to the number on the front panel on the envelope to be given to the customer as a receipt; to provide a closure flap for the open end of the envelope, which closure flap is also provided with a sealing tab portion to seal the open end of the envelope; to provide the top flap portion with a removable or tear-out section having a number or indicia corresponding to the number on the receipt and on the front panel of the envelope, said tear-out portion being placed on the contents of the envelope to be maintained thereon throughout the processing and printing of the photo finishing steps of films or the like.

Still further objects of the invention are: to provide the sealing tab with an adhesive; and to provide the closure flap with an adhesive surrounding the tear-out portion; to provide the adhesive on the closure flap with a paper cover member which also covers the tear-out portion; and to provide a device of this character simple and efficient in operation.

Other objects and advantages of this invention will become apparent from the following description taken in connection with the accompanying drawings wherein are set forth by way of illustration and example certain embodiments of this invention.

FIG. 1 is a perspective view of an envelope, showing the front face thereof.

FIG. 2 is a back view of the envelope blank used in forming the envelope of FIG. 1.

FIG. 3 is an enlarged, fragmentary section through the sealing tab, closure flap and a portion of the envelope showing the tear-out portion on the closure flap and the cover thereof.

FIG. 4 shows a back view of the envelope of a modified form of the invention without the cover paper on the sealing tab shown in FIGS. 1 to 3, inclusive, and showing the receipt extension on a side panel.

FIG. 5 is a back view of the envelope without the sealing tab on the closure flap.

FIG. 6 is a back view of the envelope showing the closure flap partially tucked in the opening thereof.

Referring more in detail to the drawings:

1 designates an envelope or container constructed in accordance with the present invention from a blank 2, as illustrated in FIG. 2. The drawings illustrate the invention as applied to an "open end" envelope, although the invention may be adaptable to "open side" envelopes, if desired.

The blank 2 has a parametric outline 3 of a standard type envelope blank providing a generally rectangular front panel portion 4, side flaps 5 and 6, bottom flap 7, and a closure flap 8. The closure flap 8 is provided with a sealing tab 9, and the bottom flap 7 is supplied with an extension member 10 providing a receipt to the customer, as will later be shown. The extension 10 is removably attached to the bottom flap 7 by a perforated line as indicated at 11.

The side flap 5 is provided on its inner face with an adhesive 12, which, when folded over the other side flap 6, will seal the envelope to form a back 13. The bottom flap 7 is provided with adhesive as indicated at 14, so that when the bottom flap is folded over the side flaps, the bottom of the envelope will be closed. The back face of the closure flap 8 is provided with adhesive 15 for closing the open top of the envelope, and the sealing tab 9 is also provided with an adhesive as indicated at 16. The sealing tab is removably secured to the closure flap by a perforated line 17.

The portion of the closure flap and particularly at substantially the center of the adhesive 15 is provided with a pullout panel 18, the pullout panel being removably secured to the flap by perforated lines as shown at 19.

5 Paper covers 20 and 28 are provided for the adhesives 15 and 16 on the closure flap and sealing tab, respectively, as illustrated in FIG. 2.

The front face 4 of the envelope is provided with an indicia or number as indicated at 21, and a like indicia or number 22 is printed upon the extension or receipt tab member 10 and on the pullout member 18 of the closure flap 8 as indicated at 23. The pullout member 18 is substantially in the center of the adhesive on the closure flap 8, for a purpose later described.

15 The front face or panel 4 is also provided with the name of the company who receives the film from the customer and includes an order as indicated at 24. The face is also provided as indicated at 25 for the name and address of the customer. Other information may be printed on the panel 4 as desired. The extension tab or member 10 is also provided with the name of the receiving company and provides a receipt for the customer.

20 In forming the envelope from the blank as described, the flap 6 is folded over the back face or inside of the front panel 4 and the flap 5 folded thereover and the adhesive secured to the outside of the flap 6. The bottom flap 7 is then folded on the fold line 26 and secured to the back 13 by the adhesive 14 to close the bottom of the envelope.

25 A roll of film or the like 27 may then be placed in the envelope and the cover portion 28 removed from the sealing tab 9, but not the adhesive on the closure flap, so that the adhesive on the sealing tab may be utilized to close the open top of the envelope.

30 In use of an envelope as described, when a customer brings a roll of film to be processed to the receiving company, the salesman or clerk places the film in the envelope, writes the name and address of the customer on the front face of the envelope, tears off the receipt or extension member 10, and gives it to the customer. The salesman then removes the cover from the sealing tab 9 and closes the envelope by use of the sealing tab. The envelope is then sent to the processor, who opens the envelope by tearing off the sealing tab 9. The film is removed from the envelope and the pullout panel or identification tag 18 is removed and placed on the roll of film 27 to maintain the identity of the film throughout the processing period. The finished pictures are then placed in the same envelope, the cover 20 over the adhesive 15 of the closure flap is removed, and the envelope is closed using the adhesive 15 as a seal. The finished envelope is then returned to the receiving store or originator, where it is given to the customer whose receipt number matches the number on the face of the envelope.

35 The adhesive on the closure flap 8 and the pullout section 18 is a nondrying pressure sensitive adhesive and the cover 20 is a release-coat paper. The adhesive on the sealing tab 9 is a reseal gum, or a nondrying pressure sensitive adhesive may be used. The pullout section is located substantially centrally of the adhesive 15 on the closure flap 8.

40 FIG. 4 shows a modified form of envelope wherein the extension or receipt member is placed upon the flap 5 as indicated at 30, removably secured thereto by a line of perforation as indicated at 31.

45 In this form of the invention, the sealing tab 9 is not provided with a cover paper, as in the preferred form of the invention. The adhesive is a resealing adhesive and will adhere to the cover paper on the closure flap for the purpose desired.

50 In FIG. 5 is shown a further form of the invention wherein the closure flap is not provided with a sealing tab portion. In this form of the invention, the cover 32 is removed so as to be able to remove the pullout panel having the number thereon to be placed on the film in the envelope for identification, and the closure flap 33 may be provided with an adhesive for sealing of the envelope, or the sealing flap 33 may be tucked in as shown in FIG. 6.

It will be obvious from the foregoing that I have provided an improved envelope or container including removable identification labels or tabs for use in processing of film or the like, not heretofore utilized in this industry.

It is to be understood that while certain forms of the invention have been described, it is not to be limited to the specific forms or arrangement of parts herein described and shown.

I claim:

1. An envelope comprising:
  - a. a rectangular panel portion and flap portions necessary to cooperate with said panel portion in providing a pocket closed along three edges by folds of said flap portions and open at the other edge to provide an insert opening to said pocket for containing material therein and said envelope having indicia suitable for use in photo finishing work and the like;
  - b. an extension member removably attached to one of said flap portions having identification indicia corresponding to identification indicia printed on said envelope;

- c. a closure flap for closing said pocket;
  - d. an identification portion of said closure flap including identification theron corresponding to identification printed on the envelope and said extension member, said identification portion being defined by weakened line for separation from said flap and for placement on and adherence to the material placed in said envelope; and
  - e. a removable sealing tab on said closure flap having adhesive thereon for engaging one of said panels for closing said opening.
2. The combination of claim 1 including:
    - a. adhesive on said closure flap for securing said flap in position closing said opening to said pocket;
    - b. a removable paper cover for said adhesive; and
    - c. the identification portion having adhesive thereon and the removable paper cover extending over adhesive on the identification portion and permitting the removal of the identification portion while said cover is in place.
